F. A. MITCHELL

DRIVING MECHANISM FOR MECHANICAL TOYS AND THE LIKE

Filed Jan. 20, 1921

Inventor
Frank Allen Stitchebe

By his Attorney
Wm. H. Block

UNITED STATES PATENT OFFICE.

FRANK ALLEN MITCHELL, OF HOVE, ENGLAND.

DRIVING MECHANISM FOR MECHANICAL TOYS AND THE LIKE.

Application filed January 20, 1921. Serial No. 433,587.

To all whom it may concern:

Be it known that I, FRANK ALLEN MITCHELL, a subject of the King of England, residing at Hove, Sussex, England, have invented certain new and useful improvements in Driving Mechanism for Mechanical Toys and the like, of which the following is a full, clear, and exact description.

This invention relates to improvements in driving mechanism or motors for mechanical toys or the like, one of the objects being to provide a motor mechanism that will be cheaper to produce than a clock work-motor and that is positive in action and easily wound up. A further object of the device is to provide a keyless motor or one that can be wound up without the use of a key. My improved motor or driving mechanism is essentially a spring operated train of gears, which is reduced to the minimum of simplicity. Other advantageous features and points of improvement will hereinafter appear.

I will now proceed to describe my invention in detail, the novel features of which I will finally point out in the appended claims, reference being had to the accompanying drawing, wherein:

Fig. 1 is a top plan view of my improved driving mechanism, a body member of a toy or the like being illustrated in dotted lines;

Fig. 2 is an enlarged fragmentary longitudinal sectional view thereof;

Fig. 3 is an enlarged top plan view of the motor-casing;

Fig. 4 is an enlarged sectional view, the section being taken on a line 4-4 in Fig. 2;

Fig. 5 is a sectional view, partly in side elevation, of a modified form of my invention; and

Fig. 6 is a fragmentary sectional plan view thereof, the section being taken on a line 6-6 in Fig. 5.

As herein embodied, my invention consists of a casing or supporting member 7 carrying shafts or axles 8 and 9, each axle carrying a pair of wheels 10 and 11. The casing 7 may be attached to the body of a toy, such as a toy-wagon, automobile or the like, said body being indicated by dotted lines 12 in Fig. 1. In this instance I have provided a spring 13 secured at one end, as at 13^a, to the casing or support 7, the opposite end being secured to one end of a movable frame 14, in this instance in the form

of an inverted trough, one wall 14^a of which carries teeth 15 to form a rack. The rack 15 meshes with a gear 16 carried by an idle shaft 17 which in turn carries a larger gear 18 meshing with a relatively small gear 19 carried by an idle shaft 20 which in turn carries a larger gear 21 meshing with a relatively small gear 22 on shaft or axle 9.

All the shafts and axles 8 and 9 will be, of course, rotatably connected to the casing 7, but shaft 17 will also be slidably supported by said casing in slots 23 (one only being shown) formed in the walls 24 and 25 of the casing 7.

One of the features of the invention is the elimination of retaining pawls to prevent spring 13 from becoming unwound or to prevent same from returning to normal position after said spring has been stretched or placed under tension. To carry out this feature of my invention, I arrange gear 18 and its shaft 17 to act as a retaining element, as well as to transmit motion to the gears 19, 21 and shaft 9. When in its normal position gear 18 will be meshed with gear 19, as illustrated in Fig. 2 and will of course be positioned at the right end of slot 23. At this time spring 13 will also be in retracted position. To wind up the spring 13, or place it under tension, a rod 25 will be pulled outwardly, causing carrier 14 to move to the left, in Fig. 2. This movement will stretch spring 13 and place it under tension and will also move shaft 17 and gear 18 to the left end of slot 23 (see dotted lines Fig. 2). When gear 18 is moved out of mesh with gear 19, it will rotate during further movement of the rack toward the left. When the pull upon the spring is released and it starts to retract, gear 18 will mesh with gear 19, thereby preventing further retraction upon the part of the spring.

To lock shaft 9 against movement, I provide a latch 26 pivotally mounted on shaft 8 and provided with a nose-piece 27 to engage either one of a pair of pins 29 carried by shaft 9.

As illustrated in Fig. 1, the spring 13 is retracted, or not under tension, and shaft 9 is held against rotation in the direction of the arrow 30.

When rod 25 is pulled toward the left, gear 18 will be drawn away from gear 19 and rotated in the direction of the arrow 31, as soon as shaft 17 is moved to the left end

of slot 23, during the tensioning of the spring. When rod 25 is released, gear 18 will mesh with gear 19 and spring 13 will remain under tension until latch 26 is released, or nose-piece 27 carried away from its engaged pin 29, after which wheels 10 and 11 on shaft 9 will rotate and the toy will travel along the support upon which it is placed, be it a table or floor.

10 To tension the spring 13 to drive the toy a predetermined distance, I provide the frame or support 7 with an elongated slot 32 (Fig. 3), having index marks 33, 34 and 35 adjacent thereto, indicating in this instance ten feet, twenty feet and thirty feet. To propel the device ten feet (for instance), the frame 14 will be moved to index mark 33, which will mean that spring 13 has been placed under sufficient tension to rotate the 20 gears and wheel sufficiently to move the toy ten feet. The same would apply to propel the device twenty or thirty feet.

15 In the form of my invention illustrated in Figs. 5 and 6, I provide a spring 36 which is connected to a rotatable slidably mounted idle shaft 37 by a cord 38, said shaft 37 being slidably mounted in slots 39 in the sides of the body member 40. The shaft 37 carries a gear 41 to engage a smaller gear 42 30 on the axle 43 for the wheels 44. The spring 36 will be placed under tension by means of a cord 45 wrapped around shaft 37. The action of this form of my invention will be the same as described for the form illustrated 35 in Fig. 1, the difference being that I have omitted the rack mechanism to rotate driving wheel 41 and substituted the cord 45, which, when drawn toward the left in Fig. 5, will rotate shaft 37, after having just 40 drawn its gear 41 away from gear 42, and stretch spring 36 or place same under tension.

45 To maintain rod 25 at all times in retracted position, excepting when pulled out, I employ a small spring 46, located within spring 13 and attached at one end to casing 7 and at the opposite end to rod 25 (see Fig. 2). When spring 13 is extended, spring 46 will be extended, but when the pull upon rod 50 25 is released, said spring 46 will return rod 25 to retracted position. By this means rod 25 will be prevented from extending beyond the end of the frame 7 when the toy is in motion, or at any time excepting when the rod is pulled out to tension spring 13. Of course, it will be understood that my improved driving mechanism can be applied to or adapted for use in connection with various types of mechanical toys, and that the 55 details of construction can be varied to suit requirements. Equivalents for the sliding free wheel action at 23 or 39 or other parts constructed and adapted to perform the proper and desired functions may be employed 60 as well.

Having described my invention, what I claim and desire to secure by Letters Patent, is:—

1. In a toy, a frame, wheels carried thereby, a carrier slidable on said frame, a spring 70 to actuate the carrier, gears associated with the wheels and actuated by said carrier, means to place said spring under tension, and means to indicate when said spring has been tensioned to actuate the carrier to operate said wheels a desired number of revolutions, whereby the toy will be propelled a predetermined distance.

10 2. In a toy, a frame having an elongated slot, wheels carried thereby, a carrier slid- 80 able along said slot, gears associated with said wheels and actuated by said carrier, an extensible spring to actuate the carrier, means to extend the spring to place same under tension, and index marks arranged along 85 said slot to indicate when said spring has been extended to produce sufficient tension to rotate the gears to actuate said wheels a desired number of revolutions, whereby the toy will be propelled a predetermined 90 distance.

3. In a driving mechanism, a frame, a rotatable driven gear supported by said frame a second driven gear meshing with the first driven gear, an extensible spring, means to extend said spring to place same under tension, free-wheeling means associated with said gears to allow the second driven gear to remain stationary while the said tensioning means is pulled to put the said spring under tension and cause the first gear to turn the second driven gear when said spring is retracting and means operated by the second driven gear.

4. In a driving mechanism, a frame, a ro- 105 tatable driven gear supported by said frame, a second driven gear meshing with the first driven gear, an extensible spring, means to extend said spring to place same under tension, free-wheeling means associated with 110 said gears to allow the second driven gear to remain stationary while said tensioning means is pulled to put the said spring under tension and cause the first driven gear to turn the second driven gear when said spring is retracting and means operated by the second driven gear, and a releasable latch to prevent rotation of the driven gear until the actuation thereof is desired.

5. In a driving mechanism, a frame, a ro- 120 tatable driven gear slidably supported by said frame, a second driven gear normally meshing with the first driven gear, an extensible spring, means to extend the spring to place same under tension, means as- 125 sociated with the spring to move the first driven gear out of mesh with the second driven gear while said spring is being tensioned, and to cause the first driven gear to again mesh with the second driven gear af- 130

ter said spring has been placed under tension.

6. In a driving mechanism, a casing, a 5
slidable rack carried by the casing, a rotat-
able gear supported by the casing and in en-
gagement with said rack, a spring connected
with the rack, a driven gear arranged to be
actuated by the gear engaging said rack,
tensioning means to move the rack to place
10 said spring under tension, free-wheeling
means associated with said gears to allow
the driven gear to remain stationary while
the said tensioning means is pulled to put
said spring under tension and cause the
15 rack operated gear to turn the driven gear
when said spring is retracting and means
operated by the driven gear.

7. In a driving mechanism, a casing, a 20
slidable rack carried by the casing, a rotat-
able gear supported by the casing and in en-
gagement with said rack, a spring connected
with the rack, a driven gear arranged to be
actuated by the gear engaging said rack,
tensioning means to move the rack to place
25 said spring under tension, free-wheeling
means associated with said gears to allow the
driven gear to remain stationary while the
said tensioning means is pulled to put said
spring under tension and cause the rack op-
30 erated gear to turn the driven gear when
said spring is retracting and means operated
by the driven gear, and a releasable latch to
prevent rotation of the driven gear until the
actuation thereof is desired.

8. In a driving mechanism, a casing, a 35
slidable rack carried by the casing, a rotat-
able gear slidably supported by the casing
and in engagement with said rack, a spring
connected with said rack, a driven gear ar-
ranged to normally mesh with the gear en-
40 gaging said rack, tensioning means to move
the rack to place said spring under tension
and to move the gear meshing with said rack
out of engagement with the driven gear
while said spring is being tensioned, said 45
movable gear being caused to mesh with the
driven gear when said tensioning means is
released, and means operated by the driven
gear.

9. In a driving mechanism, a main spring, 50
intermeshing gears actuated thereby, means
connecting said spring and one of said gears,
means to place said spring under tension and
releasably connected therewith, and means
to return the spring tensioning means to 55
normal position after the spring has been
placed under tension.

10. In a driving mechanism, a train of
intermeshing gears, a spring to actuate the
train of gears, a bodily movable driving 60
gear, means connecting the spring and driv-
ing gear, projecting tensioning means asso-
ciated with said spring, said driving gear be-
ing arranged to be moved out of mesh with
its associated gear after said spring has been 65
wound up.

FRANK ALLEN MITCHELL.
